UNITED STATES PATENT OFFICE.

THOMAS NORUM, OF BROOKLYN, NEW YORK.

FLY-SCREEN.

No. 861,140.

Specification of Letters Patent.

Patented July 23, 1907.

Application filed December 8, 1906. Serial No. 346,966.

To all whom it may concern:

Be it known that I, THOMAS NORUM, a citizen of the United States, residing at Brooklyn, in the county of Kings and State of New York, have invented certain new and useful Improvements in Fly-Screens, of which the following is a specification.

This invention appertains to means for protecting verandas, porches, and similar exposed places so as to keep off flies, mosquitoes, and like winged insects.

10 This invention provides a screen of novel structure and formed of sections which are adapted to be easily handled and quickly placed in position and adapted to be easily removed and stowed away in a small space, thereby enabling the screen to be quickly placed in 15 position during warm weather and laid aside during the cold season when exposed places, such as porches, are not infested by flies and like insects.

20 The invention contemplates a novel structure of frame and means whereby the screen material, or wire fabric, may be conveniently and expeditiously attached thereto, or removed as may be required.

25 The invention further provides peculiar securing means co-operating with the screen frame, whereby the latter may be attached to the frame-work of the porch, or like place, to be protected, and whereby positive connection is had between the screen frame and the supporting structure, so as to preclude displacement by wind, or ordinary knocks.

30 For a full description of the invention and the merits thereof and also to acquire a knowledge of the details of 35 construction of the means for effecting the result, reference is to be had to the following description and accompanying drawings.

While the invention may be adapted to different 40 forms and conditions by changes in the structure and minor details without departing from the spirit or essential features thereof, still the preferred embodiment is shown in the accompanying drawings, in which:

Figure 1 is a detail view of the invention showing the 45 same applied. Fig. 2 is a horizontal section on the line $x-x$ of Fig. 1. Fig. 3 is a detail perspective view of a portion of the screen frame showing the parts on a larger scale. Fig. 4 is a detail perspective view showing the means for connecting a door jamb to the floor, or like support. Fig. 5 is a detail view of a modified 50 form of stay. Fig. 6 is a horizontal section on the line $y-y$ of Fig. 5. Fig. 7 is an enlarged transverse sectional view through one of the stays.

Corresponding and like parts are referred to in the 55 following description and indicated in all the views of the drawings by the same reference characters.

The screen comprises frame bars, screen material, such as ordinary wire fabric, and stays between the frame bars and the sections comprising the screen to 60 stiffen and brace the latter and to overlap and secure the joints formed between the screen fabric. The

frame bars are adapted to occupy a position at the upper and lower edges of the screen, although they may be arranged in any position found most advantageous in adapting the invention to a particular location, or 65 structure to be protected. Each frame bar comprises a strip 1 and a clamp 2, said parts being of substantially the same length. The strip 1 is grooved in its outer edge, as at 3, to receive heads, or projecting parts of the fastenings employed for attaching the screen to the 70 parts of the structure to which the screen may be fitted. A rabbet 4 is provided in a side of the strip 1 adjacent to its inner edge and receives the clamp 2, the shoulder 5 formed at the inner edge of the rabbet, being under cut to overlap the beveled edge 6 of the clamp 2. The 75 clamp 2 consists of a strip which in cross section corresponds to the outline of the rabbet 4 so that when the parts are assembled and the clamp is in proper position, its outer side and edge come about flush with the side and edge of the strip 1. The screen 7 which may be of 80 any material, preferably wire fabric, has an edge portion secured between the strip 1 and clamp 2 and is held in place by means of tacks 8 which are driven into the rabbeted portion 4 of the strip 1 a distance so as to provide a space between their heads and the face 85 of the rabbeted part 4, corresponding to the thickness of the screen, the heads of the tacks being of a size to pass through the meshes of the screen and engage therewith after the fashion of a button and button-hole fastening. A groove 9 is formed in the inner face of the 90 clamp 2 to receive the heads of the tacks 8 and admit of the screen being clamped between the members 1 and 2. Screws, or fastenings 10 secure the clamp 2 to the strip 1. It will be understood that the strain upon the screen is sustained by the tacks 8, the clamp 95 2 serving to prevent the screen becoming accidentally disengaged from said tacks, and also serving in a measure to grip the screen and thereby supplement the action of the tacks 8.

It will be understood that the screen may be of any 95 length but for convenience of handling, it is made up of sections.

For stiffening and strengthening the screen, stays are located at intervals in the length thereof, each of the stays comprising companion strips 11 between which 100 the screen is clamped, and secured, screws, or fastenings 12, connecting the pairs of strips on opposite sides of the screen. The stays fit snugly between the frame bars, their ends abutting against the inner edges thereof. It will thus be understood that the stays in addition to stiffening and strengthening the screen frame, 105 also serve to provide a close joint, whereby space between the meeting ends of the screen sections is obviated.

Where portions of a screen are disposed relatively at 110 an angle to each other, as at the corner of a porch, or veranda, the frame bars have a vertical arrangement

where their meeting portions are jointed, as by means of a tongue and groove, as indicated most clearly at 13 in Fig. 2.

Where the screen is provided with a door opening, 5 the jamb 14, bordering upon the opening is constructed in substantially the same manner as a frame bar; the only difference being that the same is made wider, or heavier. The end of the jamb 14 is provided with headed fastenings by means of which clips 16 are attached to the structure to which the screen is fitted. 10 Each clip 16 is of substantially "U" form in cross section so as to embrace opposite sides of the jamb 14 and one or more slots 17 are formed in a side of the clip to receive headed fasteners 18 applied to a side of the 15 jamb.

It is preferred to secure molding, or like strips 19 to the ceiling and floor of the porch, or veranda, or like place to be screened and to have the screen fit between said moldings, or strips, as indicated most clearly in 20 Fig. 1. The provision of the molding is not essential to the efficiency of the screen and the same may be dispensed with, in which case, the screen will be secured directly to the ceiling and floor.

The clips 20 applied to the frame bars of the screen 25 are of peculiar formation, each consisting of angularly disposed members 21 and 22, and lips, or flanges 23 and 24 at the ends of the respective members 21 and 22. The member 21 extends along a side of the frame bar and its lip 23 engages the inner edge of the clamp strip 30 2. The member 22 extends over the edge of the frame bar, and its lip, or flange 24, engages with the side of the bar opposite to that adjacent to the side member 21. Each member of the clip is formed with a key-hole slot 25 adapted to receive headed fastenings, or 35 screws. The key-hole slot in the member 22 is in line with the groove 3 of the strip 1 to admit of the head of the fastening coöperating with the clip entering the groove 3 so that a close fit may be had between the frame bar and the part to which said frame bar is attached. By reason of the peculiar formation of the 40 clips 20, they may be placed in position upon the frame bars of the screen with the greatest ease and despatch and likewise readily removed therefrom when required for any purpose. It is to be understood that 45 the clips are placed in position by having the heads of the fastenings passed through the enlarged portions of the key-hole slots after which said clips are moved to cause the heads of the fastenings to overlap the contracted portions of the slots.

50 In the modification as shown in Figs. 5 and 6, it is contemplated to have the screen terminate about in line with the upper and lower frame bars; hence when the sections are placed together, the screen of each, instead of overlapping, will abut or come close together. 55 To provide a close joint, the stay is of a width to overlap contiguous end portions of the screen and one member of the stay is provided with two rows of headed fastenings 26 similar to the headed fastenings 8 and have a like purpose, viz: to pass through meshes near edges

of adjacent sections. The companion member of the 60 stay is provided with two grooves 27 corresponding to the rows of headed fastenings 26 to receive the same, the screen being clamped between the members of the stay.

For connecting the members of the stay, screw eyes 65 28 are provided and are let into one member and are adapted to have their eye ends pass through slots 29 of the member having the grooves 27, said screw eyes being given a one-quarter turn to cause their eye ends to sit crosswise of the slots 29 and hold the members of the 70 stays together.

Having thus described the invention, what is claimed as new is:

1. In a screen, the combination of a frame bar, a clamp 75 coöperating with the frame bar to hold the netting in position, a clip embracing the frame bar and clamp and serving to retain the clamp against the bar, and fastening members having an interlocking connection with the clip for supporting the screen.

2. In a screen, the combination of a frame bar having a 80 groove in its outer edge, a clip secured to the frame bar of the screen and having a portion extended over the grooved edge thereof and formed with an opening in line with the groove, and a headed fastening coöperating with the clip for securing the bar in position and adapted to have its 85 head enter the groove of the frame bar.

3. In a screen, the combination of a frame bar, a clamp 90 coöperating with the frame bar to retain the netting in position, a clip embracing the frame bar and clamp and provided with key hole slots, and headed fastenings coöperating with the key hole slots to secure the clip to the frame bar and to retain the frame bar in position.

4. In a screen, the combination of a frame bar, a clamp 95 coöperating therewith to retain the netting in position, a clip comprising angularly disposed members fitting against the edge and one side of the bar, each of said members being provided with a lip engaging respectively the opposite side of the frame bar, and an edge of the clamp, and fastening members having an interlocking connection with the clip for securing the frame bar in position and fastening 100 the clip to the frame bar.

5. In a screen, the combination of a frame bar, a clip 105 embracing opposite sides of the frame bar and extending over the edge thereof and having key-hole slots in the members fitting against the side and edge of said frame bar, and headed fastenings coöperating with the key hole slots in said clip to attach the latter to the screen frame and to support the screen in position.

6. In a screen, the combination of a frame bar having an edge thereof grooved, a clamp fitting against a side of 110 the frame bar and coöperating therewith to retain the netting in position, a clip comprising angularly disposed members fitting respectively against the grooved edge and a side of the frame bar and provided with openings, one of the openings being in alinement with the slot and each of 115 the members being formed with a lip one of the lips embracing an edge portion of the clamp while the opposite lip embraces the opposite side of the frame bar, and fastening members passing through the openings in the clip and serving to fasten the clip to the bar and to secure the 120 bar in position.

In testimony whereof I affix my signature in presence of two witnesses.

THOMAS NORUM. [L. S.]
